(57) **CLAIM**

The ornamental design for a loudspeaker, as shown and described.

DESCRIPTION

FIG. 1 is a front, top, left side perspective view of a loudspeaker showing my new design;
FIG. 2 is a rear, top, right side perspective view thereof;
FIG. 3 is a front side view thereof;
FIG. 4 is a rear side view thereof;
FIG. 5 is a left side view thereof, the right side view being the same as the right side view;
FIG. 6 is a top side view thereof; and,
FIG. 7 is a bottom side view thereof.
Broken lines illustrate portions of the article that form no part of the claimed design.

1 Claim, 7 Drawing Sheets

FIG. 1

FIG. 2

FIG. 3

FIG. 4

FIG. 5

FIG. 6

FIG. 7
